2 Sheets-Sheet 2

UNITED STATES PATENT OFFICE.

GEORGE F. SMITH, OF BALTIMORE, MARYLAND.

OVEN.

Application filed November 15, 1923. Serial No. 674,921.

To all whom it may concern:

Be it known that I, GEORGE F. SMITH, a citizen of the United States, residing at Baltimore, in the State of Maryland, have 5 invented certain new and useful Improvements in Ovens; and I do hereby declare the following to be a full, clear, and exact description of the invention, such as will enable others skilled in the art to which it 10 appertains to make and use the same.

My invention relates to ovens.

Among the objects of my invention are:—

To provide an oven with a plurality of metallic pipes forming flues and to combine 15 with the oven walls a plurality of structural steel members located and arranged to support the ends of said flues.

To provide structural steel members located and arranged to support oven flues and 20 to combine with said members a plastic heat resisting material and a plate for shielding said material.

These and further objects of my invention will be set forth in the following specification, 25 reference being had to the accompanying drawings, and the means by which said objects are effectuated will be definitely pointed out in the claims.

In the drawings:—

30 Figure 1 is a longitudinal section of an oven constructed according to my invention.

Fig. 2 is a partial section along the line 2—2 in Fig. 1 looking in the direction of the arrows.

35 Fig. 3 is a section along the line 3—3 in Fig. 1 looking in the direction of the arrows.

The drawings show an oven having one fire box and one set of flues connected therewith, but since the flues in a large oven 40 having many fireboxes are counterparts of those shown, I shall describe my invention with reference to but a single fire box and the flues connected thereto.

5 represents the fire box which may be 45 formed in any approved manner, provided with a grate of any approved type and having a fire door (not shown), to permit the introduction of fuel therein. The fire box 5 is connected by the horizontal longitudinal flues 6—6 with the horizontal transverse flue 7 and the latter is connected to the horizontal longitudinal flues 8—8. The flues 8—8 50 connect with the vertical flue 9 and the

latter connects with the horizontal transverse flue 10.

The flue 10 is formed by the front wall 11, the tile cap plate 12, the flue pipe support 13, the flue pipes 14 and the filling 15 above and between same.

The flue 10 is connected by the flue pipes 14 with the soot chamber 16 and the latter is connected by the longitudinal approximately horizontal flues 17 with the horizontal transverse flue 18, the latter communicating through the passage 19 with the chimney 20. The passage 19 may be provided with a damper 21.

The rear ends of the flue pipes 14 rest upon the wall 22 and the front ends of said pipes rest upon the support 13. The support 70 13 is composed of a plurality of I beams 31 or beams of other suitable cross section having their ends supported by the vertical longitudinal walls 23—23 and a plate 24 is also supported by said walls in contact with 75 the bottom of said beams.

The space between the beams and between the first beam and the front wall 11 is filled with plastic fire-proof material 25 such as cement or other suitable material.

The baking chamber 26 is formed by the hearth 27, wall 22, flue pipes 14 and plate 24, and the front wall is provided with the opening 28 providing access to said chamber. The front wall is also provided with 85 clean out holes 29 and 30 to provide access to the flues 10 and 18, respectively.

It is to be noted that by arranging the flue pipes 14 immediately over the baking chamber 26, I provide for the most economical use of the heat. Also that by supporting the flue pipes 14 upon the wall 22 and upon the support 13, I provide an exceedingly strong construction for the support of the pipes 14 and the filling 15.

It is also to be noted that the support 13, by reason of the use of the plate 24, the I beams 31 and the plastic filling 25, forms substantially a unitary structure having great strength; also that the plate 24 serves 100 to hold the plastic material in place while it is hardening.

While I have shown one preferred arrangement of my improved oven, it is to be understood that this is for purposes of illustration only and in no wise to limit my 105

invention to the exact elements, combinations of elements and arrangement thereof shown, for changes may be made therein without departing from the spirit of my 5 invention.

I claim:—

1. An oven comprising a fire box, a chimney, a hearth, front, rear and side walls, a flue pipe support extending from side wall 10 to side wall and consisting of beams having their ends supported in said side walls, a plate beneath said beams and plastic material between said beams and resting upon said plate, flue pipes supported at one end 15 by said rear wall and at the other by said support, a connection from said fire box to one end of each of said pipes and a connection from the other end of each of said pipes to said chimney.
2. An oven comprising a fire box, a chimney, a hearth, front, rear and side walls, a flue pipe support extending from side wall 20 to side wall and consisting of beams having their ends supported in said side walls, a plate beneath said beams supported by said side and front walls, and plastic material between said beams and resting upon said plate, flue pipes supported at one end by 25 said rear wall and at the other by said support, a connection from said fire box to one end of each of said pipes and a connection from the other end of each of said pipes to said chimney.
3. An oven comprising a fire box, a chimney, a hearth, front, rear and side walls, a 30

flue pipe support extending from side wall to side wall and consisting of beams having their ends supported in said side walls, a plate beneath said beams and plastic material between said front wall and the adjacent 40 beam and between said beams and resting upon said plate, flue pipes supported at one end by said rear wall and at the other by said support, a connection from said fire box to one end of each of said pipes and a 45 connection from the other end of each of said pipes to said chimney.

4. In an oven, the combination with front, rear and side walls and flue pipes each supported at one end by said rear wall, of a 50 support for the other ends of said pipes consisting of beams having their ends supported by said side walls, a plate beneath said beams and plastic material between said beams and resting upon said plate. 55

5. In an oven the combination with front, rear and side walls and flue pipes each supported at one end by said rear wall, of a support for the other ends of said pipes consisting of beams having their ends supported by said side walls, a plate beneath 60 said beams supported by said front and side walls, and plastic material between said front wall and the adjacent beam and between said beams and resting upon said 65 plate.

In testimony whereof, I affix my signature.

GEORGE F. SMITH.
